FLUID SIGNALING MEANS

William Wilson Reed, Los Angeles, Calif., and
John Joseph Reed, Flat River, Mo.

Application August 31, 1956, Serial No. 607,501

2 Claims. (Cl. 116—114)

This invention relates to fluid signaling means and more particularly to apparatus to be used in connection with fluid pressure supply lines of any character for transmitting information, such as a warning signal, from a central station to a plurality of separated points along the supply line. Still more particularly the invention relates to a stench warning signaling means for fluid pressure supply lines and especially to a stench warning signaling means for compressed air supply lines feeding compressed air throughout mines and industrial plants. In mines and industrial plants it is necessary to provide some means operative from a central station either manually or automatically for warning the workmen in the event of some emergency, such as fire, explosion, power failure and the like, to vacate the premises.

The object of the present invention is to provide a stench warning means adapted for utility in connection with fluid pressure lines carrying air under pressure for ventilation or for operating pneumatic devices throughout the mine or industrial plant.

Another object is to provide a stench warning means operative from a central station which means is adapted for utility in connection with fluid pressure supply lines carrying compressed air.

A further object is to provide a stench warning means operative from a central station which is adapted for utility in connection with the compressed air supply lines utilized in ventilating mines and industrial plants and in operating pneumatic machinery and equipment.

Other objects will be apparent as the invention is more fully hereinafter disclosed.

In accordance with these objects we have devised a stench warning signaling means which is adapted for wide utility in connection with fluid supply lines of all types but which is particularly adapted for utility in connection with fluid supply lines carrying air under pressure for operating pneumatic mechanisms and apparatus or for ventilation purposes in mines and factories. The stench warning signaling means of the present invention comprises in combination a pressure cylinder containing a liquid phase mixture containing a stench compound, such as a mercaptan, specifically ethyl mercaptan (C_2H_5SH) and an inert flame quenching compound, such as CCl_2F_2 and $CHClF_2$, and having an outlet opening therein normally closed by a perforable seal, a manually operative perforating valve means disposed in position over the outlet opening for perforating the seal and to permit the liquid phase mixture to escape from the cylinder at a controlled rate and a conduit connecting the outlet end of the perforating valve to the fluid pressure supply line through a shut-off valve to feed the mixture passing through the perforating valve in its gaseous phase at a controlled rate into the fluid pressure supply line.

The main problem involved in feeding a mercaptan into a compressed air line is to do so without forming an explosive mixture of air and mercaptan. The chemical

2

compounds CCl_2F_2 and $CHClF_2$, heretofore well known in the art and sold under the trademarks Freon 12 and Freon 22, are well known and recognized as inert propellants and have been variously utilized in that capacity as a propellant for a large number of compounds such as insecticides. These chemical compounds, known as Freons, also have been found to have flame quenching properties and heretofore have been utilized in connection with the projection of fire extinguishing compounds in fire extinguishing devices.

Each of these Freon compounds have flame quenching properties in mixtures of air and mercaptans where the relative proportions of mercaptan and Freon compound exceed about 1 to 5. We have discovered that when the mercaptan to Freon compound in the pressure cylinder is at least 1 to 6 the mixture in its gaseous phase may be safely introduced at any desired rate into a low or high pressure fluid pressure line carrying air where the temperatures of the air and mixture do not exceed about 100° F. As this temperature is rarely exceeded in compressed air lines, particularly in those air lines utilized for ventilation or for operating pneumatic equipment we have adapted this 1 to 6 mercaptan-Freon mixture in the stench warning signaling means of the present invention and in this mixture prefer to employ ethyl mercaptan and either Freon 12 to Freon 22 but preferably Freon 22. The chemical and physical properties of these compounds are as follows:

Freon 12 (CCl_2F_2) is a very stable, non-toxic and relatively inert gas under ordinary conditions. When compressed to 70 p.s.i.g. at 70° it becomes a liquid. When admixed with liquid phase ethyl mercaptan (C_2H_5SH) the liquid phase mixture will discharge in its gaseous phase from a pressure container at a pressure of about 70 p.s.i.g. at temperatures within the range of 70 to 80° F. This mixture is suitable for use in all fluid pressure lines carrying compressed air at pressures less than about 70 p.s.i.g. and at temperatures less than 100° F.

Freon 22 ($CHClF_2$) is a gas at ordinary temperatures but condenses to a liquid at 123 p.s.i.g. and 70° F. When liquid phase Freon 22 is admixed with liquid ethyl mercaptan (C_2H_5SH) the mixture will discharge in its gaseous phase from a pressure container at a pressure of about 123 p.s.i.g. at temperatures within the range 70 to 80° F. This mixture is suitable to use in all fluid pressure lines carrying compressed air at a pressure of less than 123 p.s.i.g. and at temperature of less than 100° F.

Ethyl mercaptan (C_2H_5SH) is a highly volatile and inflammable liquid having a boiling point of 98° F. and a flash point below —40° F. Its vapor pressure at 120° F. is 24.2 p.s.i. At atmospheric pressure its limits of flammability in air are 2.80 (lower) and 18.2 (upper) percent by volume. It is miscible in all proportions with either Freon 12 or Freon 22.

We have found that when the mixture of either Freon 12 or Freon 22 with ethyl mercaptan contains 6 parts Freon to 1 part ethyl mercaptan the mixture can be safely introduced into either low or high pressure compressed air lines without danger of explosion where the temperature of the air does not exceed 100° F., which is the maximum temperature usually present in such compressed air supply lines. For best results the mixture of Freon 22 and mercaptan should be used where the air pressure in the line exceeds 70 p.s.i.g. but not over 123 p.s.i.g. and the mixture of Freon 12 and mercaptan should be used where the air pressure in the line is less than 70 p.s.i.g.

As one specific embodiment of the invention, but not as a limitation thereof, we will disclose the invention as it has been adapted for utility as a stench warning signaling means for mines. In this field of utility most mines are

provided with compressed air lines extending to every part of the mine. This compressed air is utilized in the mine to operate pneumatic mining machines and for ventilation and usually is fed into the supply line at a pressure of about 100 p.s.i.g. For this field of utility I prefer to employ the mixture of Freon 22 and ethyl mercaptan consisting of about 6 parts Freon to 1 part ethyl mercaptan.

Referring now to the drawings:

Fig. 1 is a view illustrating the invention as adapted for use in a mine; and

Fig. 2 is an enlarged sectional view along plane 2—2 of Fig. 1 illustrating the operation of the device.

In Fig. 1 the compressed air line P carrying air under a pressure of about 100 p.s.i.g. from a source not shown is indicated as feeding the air into a pipe line p' down to one of the lower levels of a mine where it supplies air through a flexible hose H to a pneumatic drill D operated by a miner M. The air exhaust from the drill D passes out into the mine atmosphere adjacent the miner M. There are a plurality of such pieces of mining equipment actuated by air from the air line p' in the average mine.

In conformity with the present invention the stench warning means of the present invention is mounted in a position on wall W at the control center of the mine where it may be readily actuated manually in case of an emergency and, preferably, at a horizontal lever above the horizontal lever of the air line P. Cylinder C, containing approximately 100 grams of liquid ethyl mercaptan and about 600 grams of liquid Freon 22, is mounted on the wall W by means of a bracket B with the perforable sealed end E thereof down. A perforating valve V1 is mounted on the end E with the perforating pin 12 thereof aligned in perforating position with the perforable seal S on the end E. A flexible conduit means F, consisting of aluminum or copper tubing, is connected at one end to the valve outlet opening of the valve V1 by means of the fitting A1 and the other end of the conduit means F is connected by a fitting A2 to a valve V2 opening through tap T into the main air line P.

As shown in Fig. 2 the end E of the cylinder C is provided with a perforable seal S closing the opening provided therein for filling and discharging the cylinder C. In the specific embodiment shown the seal S consists essentially of an exteriorly threaded plug member 10 closing the outlet opening of cylinder C, the said plug member 10 having an axially disposed bore passageway 11 therein adapted to permit the pin 12 of the perforating valve V1 to pass freely into the passageway. The bore passageway 11 extends substantially but not entirely through the plug 10 leaving a thin wall 13 at the bottom end thereof to be perforated by the pin end 14 of the pin 12 as indicated by the dotted line position 12' of the pin 12.

Valves V1 and V2 are each common in the art and, per se, form no part of the present invention except in combination with pressure cylinder C and flexible conduit F. Valve V2 is necessary and essential to the combi-

nation of the present invention as a normally open shut-off valve in the pressure in line P to permit an empty cylinder C to be removed and replaced with a full cylinder C.

Valve V1 is a perforating valve of the type providing for pin 12 to advance to perforating position when the valve is in closed position, substantially as shown in the drawings. In rest position the valve V1 is in open position and the full pressure in line P is applied onto the plug 10 to counter balance the internal pressure in the cylinder C. To perforate the sealed end 13 of the plug 10 the valve V1 must be manually actuated from open to closed position and then re-opened sufficiently to permit the mercaptan-Freon mixture contained within the cylinder C to feed into the conduit F and through valve V2 into line P at a desired rate. At 70° F. this specific mercaptan-Freon mixture will feed into line P at a pressure of about 123 p.s.i.g. where the air pressure in the line P approximates 100 pounds and at a rate controlled by the extent to which the valve 1 is opened manually. At higher and lower temperatures the pressure within the cylinder C will vary with the temperature increasing with increase in temperature. The cylinder C should be located in a position where the temperature of the cylinder does not exceed 100° F. and does not fall under 70° F.

Having hereinabove disclosed the present invention generically and specifically and having given one specific embodiment thereof it is believed apparent that the invention may be widely varied without essentially depart from therefrom and all such modifications, changes, adaptations and departures are contemplated as may fall within the scope of the following claims:

What we claim is:

1. A signaling means for mines and the like comprising a compressed air line having an air operated tool on a terminal portion thereof, a pressurized container having therein a gaseous mercaptan stench compound such as ethyl mercaptan gas, conduit means interconnecting said container and said air line, and a valve means in said conduit means, whereby when said valve means is opened and the tool is in operation the mercaptan stench gas will issue from said tool giving the operator thereof an olfactory signal.

2. The signaling means of claim 1 wherein said pressurized container contains a non-explosive mixture of said mercaptan stench compound and one of the gaseous flame quenching compounds of the group consisting of CCl_2F_2 and CHClF_2 .
